ABSTRACT OF THE DISCLOSURE

An annular wick which can be secured to a movable wick carrier without removing the latter from the burner of a liquid fuel burning heater, said wick having secured to its outer surface at least one pair of circumferentially spaced socket members which are adapted to receive arms on the wick carrier which enter into locking engagement with the socket members when the wick is rotated relative to the wick carrier.

This is a continuation-in-part of my application Ser. No. 602,910 filed Mar. 1, 1966 now U.S. Pat. No. 3,406,003.

This invention relates to liquid fuel burning heaters of the kind in which an annular wick is detachably secured to a carrier capable of being raised and lowered by an externally operable pinion engaging a rack on the carrier.

A common method of fitting the wick to the carrier is to provide lugs on the latter which are moved circumferentially into engagement with sockets secured to the former. With such an arrangement it is usually necessary to disengage the rack from the pinion and remove the wick carrier from the burner whenever the wick requires renewal, and difficulty is often experienced in replacing the carrier due to the tendency of the lugs thereon to slip out of engagement with the sockets on the new wick.

The principal object of the present invention is to overcome this difficulty and to this end, according to the invention, at least one pair of circumferentially spaced socket members are secured to the outer surface of the wick, are adapted to receive co-operating members on the wick carrier and are movable circumferentially into locking engagement with said sockets upon rotational movement of the wick relative to the wick carrier.

A preferred embodiment of the invention will be described, by way of example, with reference to the accompanying drawings in which:

FIG. 1 is an elevational view of a wick;

FIG. 2 is a shortened elevational view of the wick taken at right angles to FIG. 1;

FIG. 3 is a perspective view of a wick carrier;

FIG. 4 is a sectional elevation of part of a burner structure incorporating the wick and wick carrier of FIGS. 1 to 3; and

FIG. 5 is a horizontal section on the line V—V of FIG. 4.

The annular wick shown in FIGS. 1 and 2 includes an upper cylindrical portion 1, the inner and outer surfaces of which are reinforced and protected by strips of adhesive tape or like material (not shown), and two separate tail portions 2 depending therefrom and which in operation extend into the fuel reservoir 3 of the burner shown in FIGS. 4 and 5 and pass between inner and outer wick tubes 4 and 5 respectively. At diametrically opposed points on the outer surface of the portion 1 of the wick there are mounted two clips 6 adapted to be engaged by

2

the arms 7 of an arcuate wick carrier 8 (FIG. 3) and each consisting of a thin metal plate shaped to fit the curvature of the wick and secured thereto by prongs (not shown) which pierce the wick fabric and are turned over on the inside thereof. Each plate is formed with a central socket portion 9 above and below which it is turned outward to provide parallel radial projections 10.

The wick carrier 8 accurately fits the inner surface of the outer wick tube 5 of the burner and is provided at its central portion with a vertical rack 12 which engages a pinion 13 on the inner end of a shaft 14 provided at its outer end with a knob or handwheel 15 for manual operation. Each arm 7 of the wick carrier 8 is formed adjacent its end with a raised portion 16 for engagement in the socket portion 9 of a clip 6 and a portion 17 comprising a continuation of the main portion of the wick carrier.

To fit the burner with a new wick to which clips 6 have already been secured, the rack and pinion 12, 13 is operated to lower the wick carrier 8 as far as it will go and the new wick is drawn down over the inner wick tube 4 until the clips are positioned about $\frac{1}{2}$ " above the upper edge of the outer wick tube 5. After ensuring, by rotation of the wick if necessary, that the clips are out of vertical alignment with the raised portions 16 of the wick carrier, the tail portions 2 of the wick are firmly grasped to prevent upward movement of the wick and the operating shaft 14 is rotated by means of the knob 15 to raise the wick carrier 8. When the raised portions 16 on the arms 7 reach a point at which they are circumferentially aligned with the socket portions of the clips 6, the wick is rotated until said raised portions enter the sockets 6. The wick carrier 8 and with it the new wick, is then lowered into the operative position in which the upper end of the carrier is wholly within the outer wick tube 5. In this position, the raised portions 16 of the wick carrier are prevented by the projections 10 from moving vertically out of the socket portions and the wick is thus firmly attached to the wick carrier 8.

I claim:

1. For use in a liquid fuel burning apparatus, the combination of an annular wick having fixed to its exterior at least one pair of circumferentially spaced outwardly open socket members, each socket member comprising an outwardly open recess with external radially projecting guide and locking portions above and below said recess, a wick carrier surrounding said wick having arms extending in opposite circumferential directions around said wick, each carrier arm having an inwardly projecting raised portion adapted to extend substantially radially from the carrier arm within the recess of an associated socket member vertically between said guide and locking portions, said projecting portions on the carrier arms and said socket members being so structurally related that said socket members may move circumferentially into locking engagement with the projecting portions on said carrier arms upon rotational movement of said wick relative to said wick carrier.

2. An annular wick according to claim 1, wherein each socket member comprises a thin metal plate shaped to fit the curvature of said wick and secured thereto by prongs which pierce the wick fabric and are turned over for attachment on the inside of said wick.
